UNITED STATES PATENT OFFICE.

DAVID ANDREWS AND CHARLES BICKERTON, OF MANCHESTER, ENGLAND; SAID
BICKERTON ASSIGNOR TO SAID ANDREWS.

APPLIANCE FOR AUTOMATICALLY AND OTHERWISE LOCKING AND UNLOCKING RAIL-WAY-CARRIAGE DOORS.

942,125.

Specification of Letters Patent. Patented Dec. 7, 1909.

Application filed April 24, 1909. Serial No. 491,943.

To all whom it may concern:

Be it known that we, DAVID ANDREWS, of 538 Gorton Lane, Gorton, and CHARLES BICKERTON, of 133 North road, Clayton, 5 both in the city of Manchester, England, and subjects of the King of Great Britain, have invented new and useful Improvements in Appliances for Automatically and Otherwise Locking and Unlocking Railway-Car- 10 riage Doors, of which the following is a specification.

Our invention relates in one arrangement to improvements in appliances for automatically locking and unlocking railway 15 carriage doors, and has for its objects to lock all the closed carriage doors automatically as soon as the train has attained a certain amount of speed and to prevent the possibility of the locked doors being opened 20 until the train has stopped, to enable any door, which has remained open through inadvertence or otherwise, to be closed after the train has started, such door being at once locked automatically by the act of closing, 25 and to unlock all the doors automatically immediately the train has come to a stand.

In carrying our improvements into effect we fit a spring bolt in the jamb of each door and we connect all the spring bolts on the 30 same side of the carriage by levers or other suitable connections passing through the side framing to a swinging rail or equivalent part suspended preferably at or about the level of the lower footboard on the carriage. 35 There is thus a swinging rail or equivalent at each side of the carriage and near one end of each rail or in any other convenient position we mount a suitable fan or equivalent, which is set in motion or moved by the 40 resistance of the air when the train attains a slight speed and by the movement of a cam or equivalent actuated either directly or indirectly by the movement of the fan the rail is moved endwise against the resistance of a 45 spring, and this movement is transmitted through the connections to all the spring bolts controlled by the rail, so that these bolts are at once shot forward into their respective doors which are thus locked and remain locked without any possibility of opening the same until the train comes to a stand- 50 still.

When the train stops and the fans cease to

actuate the cams, each spring above mentioned moves back its swinging rail and 55 through its connections withdraws the spring bolts and unlocks all the doors which it controls so that they can be opened by the ordinary handles.

When it is desired to actuate the swinging 60 rails from, say the guard's van, we dispense with the fans or their equivalents and in place of them we connect each swinging rail to the swinging rail on the adjoining carriage and couple the rail on the guard's van 65 to a hand lever under the guard's control so that he can move the lever to lock all the doors when the train starts and unlock them when the train stops.

In the event of the train starting without 70 all the doors having been closed the spring bolts allow such doors to be closed, but they are at once locked automatically by the means described and cannot again be opened until the train stops, or the doors are 75 released from the guard's van, or from the locomotive.

In the accompanying sheet of drawings,— Figure 1 is a side elevation and Fig. 2 an end view of a railway carriage to which our 80 improved appliances for automatically locking and unlocking the doors are applied.

In the drawings, *a* designates the body of a railway carriage; *b* a series of spring bolts one fitted in the jamb of each door; *c* a series of pivoted levers, connected at their upper ends to the spring bolts and at their lower ends to a swing rail; *d* the swing rail pivoted at each end to an arm *e* which is pivoted at its upper end to the carriage frame; *f* a fan or vane formed of a dished plate of metal; *g* a transverse shaft upon which the vane *f* is secured; and *h* a cam secured upon the shaft *g*, immediately in line with an arm *e* which supports the rail *d*. To prevent the vane *f* moving the cam *h* too far a stop piece *h'* is secured to the carriage frame against which the cam *h* abuts when partially turned by the vane.

There is a spring *i* behind each bolt *b*, and 100 a spring *j* secured to the carriage frame which rests against the end of the swinging rail *d* and holds it in its normal position when the carriage is stationary, the spring bolts being held back clear of the doors by 105 the levers *c*.

With the exception of the shaft *g* all the parts enumerated are duplicated upon the other side of the carriage.

In operation, when the train attains a slight speed the vane *f* by the resistance of the air will be moved back, thus partially turning the shaft *g* and the cam *h* upon it up to the stop piece *h'* and the cam acting upon the pivoted arm *e* will move it whereby the rail *d* will be moved endwise against the resistance of the spring *j* and this movement is transmitted through the levers *c* to the spring bolts *b* which will be shot forward simultaneously into their respective doors, which are thus locked and remain locked without any possibility of opening the same until the train comes to a standstill. Each spring bolt is slotted to receive a pin upon its pivoted lever *c* and has its outer end chamfered or beveled off as is well understood so that in the event of the train starting without all the doors having been closed the springs *i* and the slotted connection between the bolts and the levers will allow such doors to be closed and locked, and the doors cannot then be again opened until the train stops.

When the train stops and the vane *f* falls to its normal position, the cam *h* will be

moved to allow the spring *j* to force back the swinging rail *d*, which through its connections withdraws the spring bolts *b* and unlocks all the doors which it controls so that they can be opened by the ordinary handles.

What we claim and desire to secure by Letters Patent of the United States is:—

Means for locking and unlocking the doors of railway carriages comprising locking bolts, springs for holding the bolts in locked position, a swinging rail, levers connecting the rail to the bolts, said bolts having a slot and pin connection with the levers, a spring for normally holding the swinging rail in a position to unlock the door, a cam adapted to engage with one end of the rail, and a vane actuated by the air pressure due to the motion of the train for turning the cam into engagement with the rail to lock the door.

In testimony whereof we have signed our names to this specification in the presence of two subscribing witnesses.

DAVID ANDREWS.
CHARLES BICKERTON.
